COOL DRINK DISPENSER

William Wallace Philley, Valparaiso, Ind.

Application May 7, 1935, Serial No. 20,230

4 Claims. (Cl. 62—143)

My invention relates to improvements in a cool drink dispenser and it more especially comprises the features pointed out in the annexed claims.

The purpose of my invention is to provide a cool drink dispenser that is simple in operation; that can be economically produced; and which in the main makes use of containers such as are found on the open market. Heretofore it has been difficult to easily dispense a frozen beverage by taking advantage of its melting point and deliver the liquefied contents on demand.

With these and other ends in view I illustrate in the accompanying drawing instances of adaptation without limiting myself to the specific details shown thereon and described herein.

Fig. 1 is an elevation of a container or bottle in which the fruit juices etc. are placed to be frozen.

Fig. 2 is an elevation partly in section showing the container inverted ready to have the melted or liquefied contents withdrawn.

Fig. 3 is a top plan view of Figure 2.

Fig. 4 is a sectional elevation on an enlarged scale showing the valve connections for withdrawing liquid from the container.

Fig. 5 is a detached front elevation of the valve aligning features.

Fig. 6 is a screw cap closure for the container.

In the use of my device I may employ whatever modifications or adaptations that are necessary to meet the exigencies of varying conditions without departing from the broad spirit of the invention.

An ordinary bottle container 1 is employed in which to place liquid fruit or other juices that are to be cooled. The bottle 1 is filled only partially so as to leave an air space 5 at the top. A tube 2 with its bottom end closed is inserted in the bottle as shown in Fig. 1. The bottle is then placed in any desired refrigerator or cooler, not shown, so as to freeze the contents into a solid block of ice indicated at 3. In Fig. 1 a cracked ice refrigerant is shown simply as an exemplification of any desired freezing agent capable of solidifying the contents of the bottle. These expedients are well known, and in consequence, as noted above, are not shown.

When the frozen contents of the bottle are to be removed in a liquid state the tube 2 is first removed by pouring warm water into it to loosen the tube. This will leave an opening 4 extending throughout the entire thickness of the body of ice 3. Then the outlet mechanism 10 with its cork 8 is inserted in the neck 7 of the bottle 55 and the bottle is inverted so as to rest upon a

round opening 14 of the sheet metal support 12. This support has a base 19, a horizontal partition 13 which is provided with a centering opening 20 for the extension 15. A vertical partition 16 having a slot 17 serves to align the dispensing part of the outfit by reason of the fact that the outlet extension 18 from 10 through the valve 11 will rest in the slot 17 and thus insure that the valve 11 and the outlet extension 18 will be in the right relation on the support. The parts 10, 15, 18 and 19 constitute dispensing fitting and the upper portion of the vertical partition 16 in effect is a flange for the horizontal partition 13.

The outlet 10 has a tube 6 secured therein which tube is of such a length as to project from beneath the extension 15 up through the part 10, the hole 4 in the ice block 3, up into the air space 5. This insures that the liquid forming beneath the ice block 3 in the lower air-space 5, will freely flow through the outlet 18 when the valve 11 is opened. This means that the liquid contents will remain cool until the last portion of the ice block has melted, thus insuring that the contents will be maintained at a saleable temperature independently of external temperatures.

Instead of the cork 8 any desired form of screw cap 9 may be used in connection with the outlet 10. As soon as the container 1 is inverted on the support 12 with the outlet 10 in position the external temperature will free the ice in the container so that by gravity it will move toward the outlet 7, thus, transferring the air space at the top of the bottle in Fig. 1 to the bottom of the bottle in Fig. 2. The admission of external air into this space insures the delivery of the liquefied contents.

As shown in Fig. 1 the space 5 above the frozen liquid 3 affords ample room for the expansion of the block of ice so as to not break the container through the freezing of the liquid contents.

What I claim is:

1. The method of preparing a beverage for dispensing, which comprises the steps of partially filling a container of the bottle type having a closed bottom with the beverage material in liquid form, surrounding said receptacle with a refrigerating medium and forming said beverage into a solid block traversed centrally by a bore opening through the upper and lower faces of said block, separating said container from said medium, inverting the container and connecting the space between said bottom and said block to the atmosphere by a liquid tight passage extending through said bore and any liquid therein

and the space in the inverted receptacle below said block to means for controlling the discharge of beverage from the receptacle.

2. In a device of the character described a container having a restricted neck opening and containing a liquid partially filling the container that has been frozen with an opening therethrough extending from top to bottom, the partially filled bottle having an air space at above 10 the solid contents before and above the solid contents after the container has been inverted, in combination with a dispensing support having a relatively large round opening at its top to receive and support the inverted portion of the container 15 outside of its restricted neck, a valve controlled outlet device positioned in the opening of the container and adapted to be handled with the container as a unit, an air tube supported by the outlet device and extending upwardly through 20 the hole formed in the previously frozen ice block, and means in the support cooperating with the neck of the container through the outlet device to hold the container centrally on the support.

3. In a device of the character described, the combination of an inverted bottle, a supporting base having a top engaging the shoulders of the bottle, a partition in the base provided with an opening in alignment with the center of the bottle, said base having a wall provided with a slot, 25 a dispensing fitting having a nozzle thereon provided with a valve and secured to said bottle and adapted to be handled therewith as a unit, one

portion of the fitting projecting into the opening of the bottle and another portion extending into the opening in the partition and said nozzle being removably positioned in the slot, and means for placing the upper portion of the inverted bottle 5 into communication with the atmosphere.

4. In a device for holding a beverage bottle in inverted position and dispensing beverage therefrom, the combination with a support of an outlet mechanism; said support comprising a base; means projecting from said base and formed to provide a flanged partition substantially parallel with the base, said means being provided with a slot in the flange and an opening in the partition; a wall projecting from the base and surrounding 15 said partition and terminating in an edge formed to receive the shoulders of the bottle; said outlet mechanism comprising a coupling member having a pair of bosses projecting in opposite directions therefrom, one of said bosses being positioned in said opening and the other providing a support for the closure of the bottle; a faucet projecting from one side of the coupling member, and a tubular element extending through the last mentioned boss and arranged to introduce 20 air from the atmosphere into the interior of the bottle; said element cooperating with the walls of the last mentioned boss to form a chamber adapted to conduct the contents of the bottle to the faucet. 30

WILLIAM WALLACE PHILLEY.
